UNITED STATES PATENT OFFICE.

ALFRED E. KELLEY, OF ATLANTA, GEORGIA, ASSIGNOR TO NUGRAPE COMPANY OF AMERICA, OF ATLANTA, GEORGIA, A CORPORATION OF GEORGIA.

DESIGN FOR A BOTTLE.

Application filed February 2, 1922. Serial No. 504. Term of patent 14 years.

To all whom it may concern:

Be it known that I, ALFRED E. KELLEY, a citizen of the United States of America, and resident of Atlanta, in the county of Fulton, State of Georgia, have invented a certain new, original, and ornamental Design for Bottles, of which the following is a specification, reference being had to the accompanying drawing, forming part thereof.

The drawing is an elevation of a bottle embodying my new design.

I claim:

The ornamental design for a bottle, as shown.

ALFRED E. KELLEY.
